11 Claims. (Cl. 299—63)

1

This invention has reference to dish-washing machines, and particularly to those which can be used in the household, or in stores, restaurants or other places for effectively cleansing dishes or other small articles, without requiring the performance of manual cleansing operations on the dishes by the operator.

One of the objects of the present invention is to provide a machine of this character in which an automatic shift from the spraying of a washing fluid, which can be a mixture of water and a suitable detergent material, to the spraying of clean rinsing water, can be had without requiring stoppage of the machine.

Another object of the invention is to provide, in a machine of this character, an efficient spraying means by which a spraying head is bodily carried in a circular path and is also rotated while being so carried and which will direct either a washing fluid in jets or sprays against the dishes supported in the machine, or will direct jets or sprays of a rinsing fluid against the dishes at the option of the operator, the selected fluid being sprayed being completely under the control of the operator and being caused to be spray-distributed within the machine without requiring stoppage of the machine while the change from the spraying of one fluid to the other is being effected.

More particularly, the invention contemplates the provision of a machine having a dish container or receptacle in which an electrically-operated rotating pump impeller is contained, said impeller serving to cause the bodily movement of a spraying head in a circular path within the container or receptacle, the impeller being operative upon washing fluid to cause the same to serve as a fluid driving medium to propel the spraying head in its circular path of movement, while said spraying head is also being rotated. The invention further contemplates the provision of two separate groups of spray openings in the spraying head, one group of said openings directing jets of washing fluid against the dishes only while water inflow to the machine is shut off, while the other group of spray openings is operative to direct rinsing water against the dishes, and while so spraying, the rinsing water is operative upon valve means to prevent the spraying of the washing fluid.

These and other objects to be hereinafter pointed out, are attained by the invention, a more particular description of which will be set forth below and defined by the claims appended hereto.

In the accompanying drawings, wherein an ill-

2

lustrative embodiment of the invention is disclosed, Fig. 1 is a vertical sectional view of a dish-washing machine, constructed according to the invention;

5 Fig. 2 is a horizontal sectional view taken substantially on the line 2—2 of Fig. 1, looking in the direction of the arrows;

10 Fig. 3 is a sectional view taken on the line 3—3 of Fig. 4, said section being taken through the end of the arm or fluid manifold in which the rotating spraying head is mounted;

Fig. 4 is a sectional view taken on the line 4—4 of Fig. 3, looking in the direction of the arrows;

15 Fig. 5 is a top plan view of a portion of the spraying head;

Fig. 6 is a sectional view taken on the line 6—6 of Fig. 5, looking in the direction of the arrows;

20 Fig. 7 is a sectional view taken on the line 7—7 of Fig. 5, looking in the direction of the arrows;

Fig. 8 is a sectional view taken on the line 8—8 of Fig. 5, looking in the direction of the arrows; and

25 Fig. 9 is an enlarged fragmentary view of Fig. 1 to illustrate details more clearly.

Referring to the drawings, the dish container or receptacle of the machine is shown at 10, the same being provided with a supporting tray 11 for holding the dishes to be washed. Said tray 11 is preferably composed of metallic mesh or netting or of other foraminous construction, and it is removably supported within the container or receptacle 10 and above the bottom thereof by hanger loops 10a received in clips 11a secured to the inner face of the side wall of the receptacle 10. During the operation of the machine, the top of the dish-containing chamber or receptacle 10 is closed by a suitable removable cover not shown. At the bottom of the receptacle 10, below the dish-holding tray 11 and below the spraying means to be described, is a perforated strainer or drain 12. The water or washing fluid is heated by means of a thermostatically controlled heating device of known construction, generally indicated at 13 and located in the bottom 14 of the receptacle 10, and said heating device includes the heating coils 14a located within the receptacle.

30 Positioned centrally in the bottom 14 is a frame 15 which is rigidly secured to the bottom, said frame constituting a bearing for a tubular, vertically-disposed shaft 16 carrying the pump housing 22. Frame 15 is also provided with a coupling or connection for threadably receiving an inlet conduit 17 extending from a source of 35 water supply, such as the main water supply of

a building. The outlet conduit 18 is also connected into the frame 15.

Located concentrically within the tubular shaft 16 is a solid shaft 19. Attached to the top of the shaft 19 is a pump impeller 20, the lower end of the shaft 19 being connected either directly or by means of an intermediate propulsion device, to an electric motor 21. The pump impeller 20 is contained and rotatable within the pump housing 22 which is carried by the tubular shaft 16 and includes a lower or base portion 24, over which is secured a top or cover member 23, these two portions of the housing forming a hollow enclosure for the pump impeller 20 and also forming a radially-extending arm 25, at the outer end of which is rotatively supported a spraying head 26. The spraying head 26 is provided with a downwardly-extending vertical tubular shaft 27, the lower portion of which is shown in Fig. 4. Shaft 27 is rotatively mounted in a bearing sleeve or boss 28 arising from the lower or base portion 24 of the arm 25, this portion 24 being, as previously explained, an extended part of the pump housing 22.

Secured on the lower end of the tubular shaft 27 is a gear 29 in mesh with an idle gear 30 rotatively mounted in the part 24. The idle gear 30 meshes with a stationary ring gear 31 attached to a cup-shaped inverted strainer 32 mounted on the bottom 14 of the receptacle 10. The gearing, consisting of the intermeshed gears 29, 30 and 31, is covered at the bottom by means of a cover plate 33, attached to the under side of the housing part 24, said plate 33, together with the part 24 forming a gear chamber 34.

The shape of the pump housing 22 is such that it provides a spirally shaped wash water conveying passage 36 having an upwardly projecting portion surrounded by a neck 37 over which a downwardly directed sleeve or boss 38 provided at the lower end of the spraying head 26, is accommodated. The fit of the neck 37 and the sleeve or boss 38 is such that the water or washing fluid directed upwardly through the passage 36 will not leak out from between the neck 37 and the sleeve or boss 38 and enter the receptacle 10. A seal, consisting of a rubber or similar gasket 39 is provided between the lower half 24 of the pump housing 22 and the fixed ring gear 31. The spiral passage 36 is in communication with the interior of the pump housing 22 and dish-washing fluid, which may consist of water and a detergent mixed therewith, is forced through this passage to be sprayed against the dishes by the spraying head 26 in a manner to be described presently. In addition, a passage 40 is provided for rinsing water, said passage 40 being connected at one end with an annular portion 41, composed of the space between the shaft 19 and the concentrically-arranged tubular shaft 16, said portion 41 being in communication with the water inlet 17, so that water entering from the inlet 17 will pass into the portion 41, will enter the passage 40 and will be forced upwardly through the tubular shaft 27 to be sprayed through a pair of perforated spray tubes 42 in a manner to be presently explained.

The spraying member or head 26 is provided with two independent passages or channels for the respective distribution of the washing and rinsing fluids. For the spraying or distribution of the rinsing water, a pair of triangular or stirrup-shaped spray tubes 42 is provided, the shape and disposition of these tubes being clearly disclosed in Fig. 2. Each of these tubes is formed

in its top area with a plurality of spaced, upwardly directed perforations or spray openings 43 through which the rinsing water is directed against the dishes or other articles to be washed and which are supported upon the foraminous tray 44. The spray tubes 42 are situated above the top of the spraying head 26 through which the dish-washing fluid is directed and sprayed. Each of the spray tubes 42 is connected to a chamber 44 which communicates with the tubular shaft 27 so that the rinsing water directed therethrough will enter the tubes 42 and be sprayed out of the perforations 43 in jets against the dishes or other articles resting on the tray 44.

The body of the spraying head 26 is preferably, but not necessarily, made of cast non-corrosive metal and is of elliptical or ovate shape as seen in Fig. 2. The body of the spraying head 26 includes a lower or base portion 45 on which the sleeve 38 is provided, an intermediate frame member 46, and a top member 48. The top member 48 forms the bottom and top walls of the chamber 44. The intermediate frame 46 is grooved near its edges and in said grooves are seated straps 49, as shown in Figs. 5, 7 and 8, to form outer walls for the grooves and thus provide a channel or passage 50 for the dish-washing fluid.

The lower or base portion 45 of the spraying head 26 and the portion 46 are connected by the screws 52, and the top member 48 is attached to the part 46 by the screws 53. The top member 48 constitutes a central or hub portion for the spraying member, such member 48 being secured on the tubular shaft 27 so that, when the shaft 27 is rotated by the gears 29, 30 and 31, the spraying head 26 will also be rotated at the same time. Between the base member 45 and the central portion of the upper part of the portion 46 are provided passages 54 which establish communication between the passage 36 and the passage 50 in the spraying head. In the spraying head 26 are provided a plurality of outlet or spray openings indicated at 55 extending vertically and being directed upwardly, while those in the group designated at 56 extend upwardly and obliquely. Through these spray openings 55 and 56 the washing fluid is directed upwardly against and around the dishes or other articles supported on the tray 44.

The two straps 49, forming outer walls for the passage 50, are preferably composed of resilient or flexible material and are installed by being slid into the grooves in the frame part 46 from either of the narrower ends of the spraying head, the straps being accommodated in grooves 57 in the frame part 46 of the spraying head, as shown in Figs. 7 and 8. It will be noted that the straps 49 do not entirely surround the spraying head, but that each of the narrowed ends of the spraying head is provided with a sealing piece 47 held in seated position by a coil spring 58 which surrounds a spindle 58a. The spring and head of the spindle 58a maintain the sealing piece in its correct position.

Provided in the spraying head 26 is a valve device controlled by the flow of rinsing water, and said device is located in a chamber formed by the top member 48 in co-operation with the central or hub portion of the frame 46, said valve device consisting of a rubber-coated differential piston 59 and a seat 60 provided in the lower member 45 of the spraying head around an an-

nular channel 61. The piston 59 is biased to its upper open position by a coil spring 62, as best shown in Fig. 9. As shown in Fig. 1, the receptacle or container 10 of the machine is provided with an overflow outlet 63 connected to the outlet 18 in any suitable manner.

Briefly, the operation of the machine is as follows:

The dishes or other articles to be washed, are placed upon the foraminous tray 11 in the receptacle 10, and water introduced under line pressure flows through the inlet 17 into the annular passage 41 located between the two shafts 16 and 19. The water flows therefrom through the passage 40 and through the tubular shaft 27, into the spray tubes 42 and out of the spray openings 43 therein to fill the container 10 to a water level determined by the position of the overflow outlet 63. When the water reaches this level in the receptacle, the inflow is manually shut off and the machine is then ready for operation. The water delivered into the machine as above described, has simultaneously flowed into the interior of the pump housing 22, having reached the same through the bottom strainer 12 and the cup-shaped strainer 32. Motor 21 is now set in operation, and shaft 19, being thereupon rotated, will rotate the pump impeller 20 which will impart a rotating movement to the fluid in the pump housing so that the fluid will act as a driving medium to rotate the pump housing 22. While the pump housing is being rotated as above described, the rotation of the pump impeller 20 forces the washing water out of the jet openings 55 and 56 in the spraying head 26, the water jets or sprays emanating therefrom impinging against the dishes or other articles supported on the tray 11, while the arm 25 of the pump housing is carrying the spraying head 26 through a circular path of movement within the receptacle 10. Also, by the rotation of the pump housing 22, rotation of the shaft 27 and hence rotation of the spraying head 26 also occurs. This rotating movement of the spraying head 26 is effected by means of the gears 29, 30 and 31, the gears 29 and 30 rotating around the fixed ring gear 31, thus securing a planetary movement.

When the machine has been in operation for a sufficient period to enable the dishes to be thoroughly cleansed, and which may be facilitated by the employment of a suitable detergent in the washing water, the inlet 17 is then opened to permit the inflow of fresh water for rinsing. As the fresh water enters through the passages 17, 41, 49, 27 and 42 as heretofore described, it is sprayed out through the spray holes 43 in the tubes 42. This spraying of the rinsing water takes place of course, while the spraying head is being carried around the inside of the receptacle 10 in a circular path of movement and while the head, which includes the tubes 42, is being rotated with the tubular shaft 27 as its axis. As the rinsing water flows in the manner described, a portion of it will flow through a port 70 in the top member 48 to reach the chamber in which the piston valve 59 is situated, thereby exerting sufficient pressure against the piston valve 59 to force it downwardly against its seat 60, thus shutting off communication between the passages 54 and 36, as best shown in Fig. 9. It will thus be clear that while spraying of the rinsing water is taking place, the spraying of the washing water is discontinued. When the inlet 17 is manually closed, after the dishes have been sufficiently rinsed, the piston

valve 59 is automatically returned to its open position, as shown in Fig. 1, by the spring 62. It will be understood that as long as the electric motor 21 is energized and the shaft 19 is rotated thereby, the pump impeller 20 will be rotated to cause rotation of the pump housing 22; and rotation of the pump housing, in co-operation with the planetary gearing 29, 30 and 31, will cause bodily movement of the spraying head 26 in a circular path of movement around the vertical axis of the machine, as well as cause rotating movement of the spraying head with the shaft 27 as its axis. It will also be apparent that the change from spraying of a washing fluid to spraying of rinsing water, will be effected simply by opening the water inlet 17 to introduce rinsing water which will, by pressure on the piston valve 59, control the spraying operation and automatically cause a shift from washing to rinsing.

Accordingly, it will be understood that the operation of the machine simply involves filling the machine with washing fluid to the required height, allowing the machine to operate for a predetermined period during which time the washing fluid is being sprayed against and around the dishes, and then permitting clean water to flow into the machine, the latter action automatically causing cessation of spraying of the washing fluid and initiating spraying of the rinsing water; these operations of shifting from washing to rinsing being conducted while the motor 21 is energized and while the shafts 16 and 19 and parts associated therewith are being rotated.

While I have described one embodiment of the invention, it is obvious that the same is not to be restricted thereto, but is broad enough to cover all structures coming within the scope of the following claims.

What I claim is:

1. In apparatus of the kind described, a movable spraying device including first spraying means having one inlet and a second spraying means having another inlet, each spraying means being formed with an independent group of discharge openings from which liquid is adapted to be sprayed against dishes and the like to be washed, said movable device comprising unitary structure forming a first passageway having an inlet adapted to receive a first kind of treating liquid and communicating only with the inlet of said first spraying means and also forming another second passageway having an inlet adapted to receive a second kind of treating liquid and communicating only with the inlet of said second spraying means, a valve in said first passageway which is movable between open and closed positions, biasing means operable to move said valve toward its open position, said valve being constructed and arranged to move toward its closed position against the action of said biasing means responsive to force developed by flow of the second treating liquid in said second passageway, said first passageway including a pump for effecting flow of the first treating liquid from the inlet of such passageway toward said first spraying means, said pump comprising a movable housing forming a part of said unitary structure and a rotatable member therein for effecting such flow of first treating liquid in said first passageway, power driven means for driving said member during operation of the apparatus, the interior of said housing being formed and arranged to be acted upon by liquid circulated therein by said member to induce movement of said housing and hence impart movement to said spraying device, and

said valve being disposed in said first passageway at a region between said pump and said first spraying means to enable said member to impart movement to said spraying device when said valve is in its closed position and flow of the first treating liquid to said first spraying means is shut off.

2. In dish washing apparatus, a rotatable spraying device including first spraying means having one inlet and a second spraying means having another inlet, each spraying means being formed with an independent group of discharge openings from which liquid is adapted to be sprayed against dishes and the like to be washed, said rotatable device comprising unitary structure forming a first passageway having an inlet and communicating only with the inlet of said first spraying means and also forming another second passageway having an inlet and communicating only with the inlet of said second spraying means, provisions for introducing liquid discharged from said first spraying means to the inlet of said first passageway for flow therethrough and for only introducing rinsing liquid under pressure from a source of supply to the inlet of said second passageway for flow therethrough, a valve in said first passageway which is movable between open and closed positions, biasing means including a resilient element operable to move said valve toward its open position, said valve being constructed and arranged to move toward its closed position against the action of said biasing means responsive to force developed by flow of rinsing liquid in said second passageway, said first passageway including a pump for effecting flow of washing liquid from the inlet of such passageway toward said first spraying means, said pump comprising a rotatable housing forming a part of said unitary structure and a rotatable member therein for effecting such flow of washing liquid in said first passageway, power driven means for driving said member during operation of the apparatus, the interior of said housing being formed and arranged to be acted upon by washing liquid circulated therein by said member to induce rotation of said housing and hence impart rotating movement to said spraying device, said pump being disposed in said first passageway ahead of said valve in the direction of flow of washing liquid therethrough and said member being operable, therefore, to impart rotating movement to said spraying device when said valve is in its closed position and flow of washing liquid to said first spraying means is shut off during periods when rinsing liquid is flowing in said second passageway to said second spraying means.

3. In dish washing apparatus, a movable spraying device including first spraying means having one inlet and a second spraying means having another inlet, each spraying means being formed with an independent group of discharge openings from which liquid is adapted to be sprayed against dishes and the like to be washed, said movable device comprising unitary structure forming a first passageway having an inlet adapted to receive washing liquid and communicating only with the inlet of said first spraying means and also forming another second passageway having an inlet adapted to receive rinsing liquid and communicating only with the inlet of said second spraying means, a combined pump and fluid drive unit operatively connected in said first passageway for effecting flow of washing liquid therethrough toward said first spraying means and

constructed and arranged to make use of such washing liquid for imparting movement to said spraying device, a valve in said first passageway which is movable between open and closed positions, and biasing means including a resilient element operable to move said valve toward its open position, said valve being constructed and arranged to move toward its closed position against the action of said biasing means responsive to force developed by flow of rinsing liquid in said second passageway, and said pump and fluid drive unit being disposed in said first passageway ahead of said valve in the direction of flow of washing liquid therethrough and said unit being operable, therefore, to impart movement to said first spraying means when said valve is in its closed position and flow of washing liquid is shut off during the periods when rinsing liquid is flowing in said second passageway to said second spraying means.

4. In dish washing apparatus, a rotatable spraying device including first spraying means having one inlet and a second spraying means having another inlet, each spraying means being formed with an independent group of discharge openings from which liquid is adapted to be sprayed against dishes and the like to be washed, said rotatable device comprising unitary structure forming a first passageway having an inlet and communicating only with the inlet of said first spraying means and also forming another second passageway having an inlet and communicating only with the inlet of said second spraying means, provisions for supplying a first kind of treating liquid discharged from said first spraying means to the inlet of said first passageway for flow therethrough and for supplying a second kind of treating liquid from a source of supply to the inlet of said second passageway for flow therethrough, a combined pump and fluid drive unit operatively connected in said first passageway for effecting flow of the first treating liquid therethrough toward said first spraying means and constructed and arranged to make use of such liquid for imparting rotating movement to said spraying device, valve means in said first passageway which is movable between open and closed positions, and biasing means operable to move said valve means toward its open position, said valve means being constructed and arranged to move toward its closed position against the action of said biasing means responsive to force developed by flow of the second treating liquid in said second passageway, and said valve means being disposed in said first passageway at a region between said pump and fluid drive unit and said first spraying means to enable said unit to impart rotating movement to said spraying device when said valve means is in its closed position and flow of the first treating liquid to said first spraying means is shut off.

5. In apparatus of the kind described, a movable spraying device including a spray head having first and second inlets for liquid, said spray head being formed with two groups of discharge openings from which liquid is adapted to be sprayed against dishes and the like to be washed, said first spray head inlet communicating only with one group of discharge openings and said second spray head inlet communicating only with the other group of discharge openings, all of said discharge openings and both of said inlets forming a part of a movable unitary body, said movable device comprising unitary structure forming a first passageway having an inlet adapted to

receive a first kind of treating liquid and communicating only with said first spray head inlet and also forming another second passageway having an inlet adapted to receive a second kind of treating liquid and communicating only with said second spray head inlet, a valve in said first passageway which is movable between open and closed positions, biasing means operable to move said valve toward its open position, said valve being constructed and arranged to move toward its closed position against the action of said biasing means responsive to force developed by flow of the second treating liquid in said second passageway, said first passageway including a pump for effecting flow of the first treating liquid from the inlet of such passageway toward said first spray head inlet, said pump comprising a movable housing forming a part of said unitary structure and a rotatable member therein for effecting such flow of first treating liquid in said first passageway, power driven means for driving said member during operation of the apparatus, the interior of said housing being formed and arranged to be acted upon by liquid circulated therein by said member to induce movement of said housing and hence impart movement to said spraying device, and said valve being disposed in said first passageway at a region between said pump and said first spray head inlet to enable said member to impart movement to said spraying device when said valve is in its closed position and flow of the first treating liquid to said first spray head inlet is shut off.

6. In apparatus of the kind described, a movable spraying device including a spray head having first and second inlets for liquid, said spray head being formed with two groups of discharge openings from which liquid is adapted to be sprayed against dishes and the like to be washed, said first spray head inlet communicating only with one group of discharge openings and said second spray head inlet communicating only with the other group of discharge openings, all of said discharge openings and both of said inlets forming a part of a movable unitary body, said movable device comprising unitary structure forming a first passageway having an inlet and communicating only with said first spray head inlet and also forming another second passageway having an inlet and communicating only with said second spray head inlet, provisions for introducing a first kind of treating liquid to the inlet of said first passageway for flow therethrough and for introducing a second kind of treating liquid to the inlet of said second passageway for flow therethrough, a combined pump and fluid drive unit operatively connected in said first passageway for effecting flow of the first treating liquid therethrough toward said first spray head inlet and constructed and arranged to make use of such first treating liquid for imparting movement to said spraying device, a valve in said first passageway which is movable between open and closed positions, and biasing means including a resilient element operable to move said valve toward its open position, said valve being constructed and arranged to move toward its closed position against the action of said biasing means responsive to force developed by flow of the second treating liquid in said second passageway, and said valve being disposed in said first passageway at a region between said pump and fluid drive unit and said first spray head inlet to enable said unit to impart movement to said spraying device when said valve is in its closed position and flow

of the first treating liquid to said first spray head inlet is shut off.

7. In apparatus of the kind described, a movable spraying device including a spray head having first and second inlets for liquid, said spray head being formed with two groups of discharge openings from which liquid is adapted to be sprayed against dishes and the like to be washed, said first spray head inlet communicating only with one group of discharge openings and said second spray head inlet communicating only with the other group of discharge openings, all of said discharge openings and both of said inlets forming a part of a movable unitary body, said movable device comprising structure forming a first passageway having an inlet and communicating with said first spray head inlet and also forming another second passageway having an inlet and communicating with said second spray head inlet, provisions for supplying a first kind of treating liquid to the inlet of said first passageway and flowing such liquid therethrough to said first spray head inlet and for supplying a second kind of treating liquid to the inlet of said second passageway and flowing such liquid therethrough to said second spray head inlet, a valve in said first passageway which is movable between open and closed positions, biasing means including a resilient element operable to move said valve toward its open position, said valve being constructed and arranged to move toward its closed position against the action of said biasing means responsive to force developed by flow of the second treating liquid in said second passageway, said provisions including a power driven fluid drive unit operatively connected in said first passageway and constructed and arranged to make use of the first treating liquid to impart movement to said spraying device, and said valve being disposed in said first passageway at a region between said first spray head inlet and said fluid drive unit to enable the latter to impart movement to said spraying device when said valve is in its closed position and flow of the first treating liquid to said first spray head inlet is shut off.
8. In apparatus of the kind described, a movable spraying device including first spraying means having one inlet and second spraying means having another inlet, each spraying means being formed with an independent group of discharge openings from which liquid is adapted to be sprayed against dishes and the like to be washed, said movable spraying device comprising unitary structure forming a first passageway having an inlet and communicating with the inlet of said first spraying means and also forming another second passageway having an inlet and communicating with the inlet of said second spraying means, provisions for supplying washing liquid to the inlet of said first passageway and flowing such liquid therethrough under pressure to said first spraying means and for supplying rinsing liquid from a source of supply to the inlet of said second passageway and flowing such liquid therethrough under pressure to said second spraying means, a valve in said first passageway which is movable between open and closed positions, biasing means operable to move said valve toward its open position, said valve being constructed and arranged to move toward its closed position against the action of said biasing means responsive to force developed by flow of rinsing liquid in said second passageway, said provisions including a power driven fluid drive unit operatively connected in said first passageway and constructed and arranged to make use of washing

liquid to impart movement to said spraying device, said valve being disposed in said first passageway at a region between said first spraying means and said fluid drive unit to enable the latter to impart movement to said spraying device when said valve is in its closed position and flow of washing liquid to said first spraying means is shut off.

9. In dish washing apparatus, a spraying device including first spraying means having one inlet and a second spraying means having another inlet, each spraying means being formed with an independent group of discharge openings from which liquid is adapted to be sprayed against dishes and the like to be washed, said device comprising structure forming a first passageway having an inlet and communicating only with the inlet of said first spraying means and also forming another second passageway having an inlet and communicating only with the inlet of said second spraying means, provisions for only supplying a first kind of treating liquid to the inlet of said first passageway and for only supplying a second kind of treating liquid to the inlet of said second passageway, a valve in said first passageway which is movable between open and closed positions, and biasing means including a resilient element operable to move said valve towards its open position, said valve being constructed and arranged to move toward its closed position against the action of said biasing means responsive to force developed by flow of the second treating liquid in said second passageway, thereby automatically shutting off the supply of the first treating liquid through said first passageway to said first spraying means whenever the second treating liquid is being supplied through said second passageway to said second spraying means.

10. In dish washing apparatus, a spraying device comprising first spraying means having one inlet and second spraying means having another inlet, each spraying means being formed with an independent group of discharge openings from which liquid is adapted to be sprayed against dishes and the like to be washed, said device comprising structure providing a first passageway having an inlet and communicating only with the inlet of said first spraying means and also providing another second passageway having an inlet and communicating only with the inlet of said second spraying means, provisions for introducing washing liquid discharged from said first spraying means to the inlet of said first passageway for flow therethrough and for only introducing rinsing liquid under pressure from a source of supply to the inlet of said second passageway, a valve in said first passageway which is movable between open and closed positions, and biasing means including a resilient element operable to move said valve toward its open position, said valve being constructed and arranged to move toward its closed position against the action of said biasing means responsive to force

developed by flow of rinsing liquid in said second passageway, thereby automatically shutting off the supply of washing liquid through said first passageway to said first spraying means whenever rinsing liquid is introduced to said second passageway for flow therethrough to said second spraying means.

11. In apparatus of the kind described, a rotatable spraying device including a spray head having first and second inlets for liquid, said spray head being formed with two groups of discharge openings from which liquid is adapted to be sprayed against dishes and the like to be washed, said first spray head inlet communicating only with one group of discharge openings and said second spray head inlet communicating only with the other group of discharge openings, all of said discharge openings and both of said inlets forming a part of a rotatable unitary body, said rotatable spraying device comprising unitary structure forming a first passageway having an inlet and communicating only with said first spray head inlet and also forming another second passageway having an inlet and communicating only with said second spray head inlet, provisions for supplying a first kind of treating liquid to the inlet of said first passageway and for supplying a second kind of treating liquid to the inlet of said second passageway, a valve in said first passageway which is movable between open and closed positions, and biasing means including a resilient element operable to move said valve toward its open position, said valve being constructed and arranged to move toward its closed position against the action of said biasing means responsive to force developed by flow of the second treating liquid in said second passageway, thereby automatically shutting off the supply of the first treating liquid through said first passageway to said first spray head inlet whenever the second treating liquid is being supplied through said second passageway to said second spray head inlet.

JOHAN FREDRIK ROBERT KARLSTROM.
